UNITED STATES PATENT OFFICE.

WILFRID LUMLEY, OF CONNEAUT, OHIO, ASSIGNOR TO GENERAL ELECTRIC COMPANY,
A CORPORATION OF NEW YORK.

LIGHTING-FIXTURE.

1,206,561.

Specification of Letters Patent. Patented Nov. 28, 1916.

Application filed September 26, 1913. Serial No. 791,982.

To all whom it may concern:

Be it known that I, WILFRID LUMLEY, a citizen of the United States, residing at Conneaut, in the county of Ashtabula, State 5 of Ohio, have invented certain new and useful Improvements in Lighting-Fixtures, of which the following is a specification.

My invention relates to lighting fixtures, and more particularly to those of the elec- 10 tric type.

My invention comprises various novel features of construction and combinations and arrangements of parts which can best be set forth by the description of a particular 15 structure embodying it, and I have accordingly hereinafter described such a structure together with various accessory features and modifications.

Among the advantages which may be ob- 20 tained through my invention are the mounting of electric lamps of large candle power in such a manner that the portion of the fixture which receives the base of the lamp and is therefore most liable to be heated by 25 conduction from the lamp, is ventilated so that overheating is impossible and the protection of all the parts from the weather when the fixture is mounted out of doors. As will also be apparent from the structure 30 hereinafter described, the fixture and its parts are simple and inexpensive of construction, present a good appearance, and are rugged and durable. Various other ad- 35 vantages obtainable through the invention will hereinafter appear. It will of course be apparent to those skilled in the art that the invention may be embodied, carried out and applied in forms different than those shown and described, as indicated by the 40 scope of my claims.

In the accompanying drawing, Figure 1 is a perspective view of a fixture constructed in accordance with my invention and attached to a bracket adapted to be secured 45 to a wall, a post, or the like; Fig. 2 is a view of such a fixture with certain modifications as regards the character and mounting of the reflector and the mounting and support of the fixture itself, the modification last mentioned being such as to adapt the fixture for mounting close to a ceiling; Fig. 3 is a perspective view of one of the parts shown in Fig. 1 as it appears when separated from the rest after the fixture has been detached 50 from the bracket arm; Fig. 4 is a plan view

of certain interior parts as seen after the detachment and removal of the bracket and the part illustrated in Fig. 3; Fig. 5 shows the fixture with a form of shade illustrated in Fig. 2 but with a suspension member at- 60 tached to the top such as may be employed when it is desired to suspend the fixture by a chain, and in this figure the upper part shown in Fig. 3 appears in mid-section and the lower portion is shown as in section 65 along the broken line 5—5 in Fig. 4; Fig. 6 shows the lamp socket and associated electrical parts as removed from the rest of the fixture; Fig. 7 shows a modified form of 70 socket adapted to take a small lamp and illustrates the manner in which it is to be mounted in place of the larger one.

Referring first to Figs. 1, 2, 3, 4, and 5, it will be seen that the fixture comprises a main body portion 1 and various other parts 75 attached to or associated with it. In Fig. 1, it will be seen that the body 1 holds a shade 2 of white porcelain or any other suitable material, and that at the top of the fixture there is a fitting 3 threaded or otherwise secured on one end of a tubular bracket arm 4 attached to a suitable bracket 5 adapt- 80 ed to be screwed or bolted to a wall or post or any other object by screws extending through holes 6.

In Fig. 2 the parts shown with the body portion 1 comprise a metal reflector 8 and a holder 9 which fits about the upper portion of the body and is secured thereto by set screws 10 which engage in holes in the body 90 portion 1 or beneath a flange or a part at- 95 tached thereto. In Fig. 5 it will be seen that a fitting 4^a is secured above the body 1, this fitting being provided with a ring 4^b by means of which the fixture may be sus- 100 pended by a chain or in any other desired manner.

Referring, now, more particularly to Figs. 3, 4, and 5, it will be seen that the body 1 carries a socket 11 (shown as of the ordinary Edison screw type) for engaging with the base of a lamp. This socket, it will be seen, is mounted in a cavity 12 at the lower side of the body 1. The reflector 8 of the type shown in Fig. 5 has an upwardly pro- 105 jecting flange 13 which fits about the lower end of the body 1. The portion of the reflector within this flange has notches 14, one of which is shown at the right of the figure, which fit about the shanks of screws 15 en- 110

gaging with suitable metallic parts carried by the body, and the shade is in this manner securely mounted beneath the reflector and at the same time easily removable. This shade may be of any desired construction and of any suitable material, such, for example, as enameled sheet metal.

As will be seen from Figs. 4 and 5, the electrical connections to the socket 11 are made at the upper side of the body 1 and are covered by a part 16 mounted above it, which, as shown, is separable from the body 1. As shown in Figs. 3 and 5, this cover is a dome shaped flat piece having its lower edge slightly under-cut so that when it rests on the upper end of the part 1 it may extend down below the upper end of the part 1 or ring and so keep out the weather. As shown in Figs. 1 and 5, the part 4 or 4^a by 15 which the fixture is supported is fastened to two brackets 17 secured to the part 1 extending up through holes 18 in the cover 16 and having in their upper ends threaded holes for screws 19 which pass through holes 20 in the sides of the tubular lower end of the part 4 or 4^a. In the boss 22 at the upper side of the part 16 are holes 23 through which the electric wires may be introduced into the fixture, as shown in Fig. 5, although such wires may also enter the fixture in other ways as will hereafter appear. It will be seen that when the part 4 or 4^a is in place and the other parts arranged as shown in Figs. 1 and 2, the upper side of 30 the fixture is completely water-proof. It will be seen from Figs. 4 and 5 that in the cylindrical wall of the body which surrounds the cavity 12 in which the socket 11 is mounted there are a number of vertical 35 passages 24 having the form of cylindrical holes, these passages extending from the lower side or end of the body clear up to its upper side or end. It will further be seen that the upper end of the body 1 is enlarged 40 by a flange-like outward extension 25, and that in the flange 25 are a number of vertical holes or passages 26 which extend from its lower side to the upper side of the body. It will readily be seen that when the lamp 45 is in place in the socket the heat from it will cause the air beneath the reflector to move upward from the passages 24 into the space between the upper side of the body 1 and the lower side of the dome-like cover 16, whence it will pass downward through the upper passages 26 and escape, this exit 50 from the space beneath the dome 16 being facilitated by the cooling action resulting from the exposed surface of the dome and of the flange 25.

Referring, now, to the direct electrical connections of the socket, it will be seen from Figs. 4, 5 and 6 that the socket comprises a threaded shell 30 shaped like a screw cap with a wide transverse cut in its

upper end. It will be seen that the upper end of this shell fits against the bottom of the cavity 12, a projecting portion 31 in the bottom of the cavity lying in the cut in the upper end of the shell and by its engagement with it in this manner preventing it from turning. This shell is secured in place by screws 32 which extend up through holes in the bottom of the shell and in the bottom of the cavity and engage with internally threaded holes in a metallic part above. The center contact of the shell is formed by a part 33 which fits in a shallow groove in the projecting portion 31 in the bottom of the cavity and is secured by a screw 34 in 80 very much the same manner as the shell itself. This center contact has a spring-like form so as to yield somewhat when the lamp is screwed into the socket.

The electrical connections from the socket 85 to the wires are made through the screws 32 and 34. As will be seen from Fig. 4, there is in the upper side of the body 1 a crescent shaped cavity 35. At the bottom of this cavity is a correspondingly shaped metal 90 piece 36 (Figs. 4 and 5) whose ends receive the screws 32 and at whose middle portion is a lug 37 to which one wire may be secured by a screw 38. In the other side of the part 1 is also another cavity 39 in which is a 95 part 40 (see Fig. 6) which receives and engages the screw 34 and has an upwardly extending lug 41 to which the other wire may be secured by a screw 42. Thus the connections of the wires are made and the 100 portions of them from which the insulation is removed for this purpose are located at points separated by the wall 43 between the cavities 35 and 39.

The socket shown in Figs. 5 and 6 is a 105 large one adapted to take the large base commonly used on lamps of 200 watts or more. In Fig. 7, however, is shown a small socket of the size adapted for lamps of comparatively low wattages in the cavity 12 in place of the socket 11. This socket comprises a base portion 50 having a shallow transverse groove 51 in its upper side so that it is adapted to fit the bottom of the cavity 12 and having its lower side formed very much like the bottom of the cavity 12 itself, except that it has a central cylindrical projection 52 with a cavity 53 therein. The threaded shell 54 has an upwardly extending flange 55 at its upper end. In the cavity 53 is arranged a center contact 56 of ordinary form. The screws 32 and 34^a which secure the socket and the center contact pass up through holes in the porcelain part 50 and on up through the holes in the bottom of the cavity 12 and engage the parts 36 and 40 just as in the case of the other form of socket.

It will be seen that in the midst of the 130 passages 24 are two diametrically opposite

vertical holes 60 (only one of which appears in Fig. 5). The lower portions of these holes are square in cross-section and contain parts consisting, as shown, of short strips of metal 60' with their ends bent at right angles and having threaded holes therein. The upper ends of these strips receive and engage screws 61 which pass through lugs at the lower ends of the parts 17 and so 10 serve at once to secure the parts 60' and 17 in place. It will be observed that owing to the shape of the holes 60 the parts just described cannot turn in them and that the lugs at the lower ends of the parts 17 lie in grooves 15 in the upper side of the part 1 and so are prevented from turning. It will also be seen that the lower ends of the parts 60' receive and engage the screws 15 previously mentioned by which the reflector 8 is held 20 in place.

In the arrangement shown in Fig. 1, the wires 21 enter the body through two of the holes or passages 26.

As shown in the drawings, the various 25 portions of the body 1 may be made integral with one another and, to secure the necessary insulation of the various electrical parts, the body may conveniently be made wholly of insulating material such as porcelain or bisque. As shown, the cover 16 is also made of similar material. These parts can be made in a mold of simple construction in a manner well understood by those skilled in the art. The various metallic parts are all of simple forms and can be easily and cheaply made in various well known ways. The parts are themselves simple and can be readily and quickly assembled and taken apart.

40 What I claim as new and desire to secure by Letters Patent of the United States, is:—

1. An electric lighting fixture comprising an insulating block having therein means for supporting an electric lamp and electrical connections therefor, a cover extending over the top of the said block and supported thereby, a reflector or shade holding means, and means for supporting the latter independently of the said block.

50 2. An electric lighting fixture comprising an insulating block having therein means for supporting an electric lamp and electrical connections therefor, a reflector or shade holding means below said block, and means extending through the said block for supporting the said reflector or shade holding means independently thereof.

3. An electric lighting fixture comprising

an insulating block having means therein for supporting an electric lamp and electrical connections therefor, a cover for the said block, a reflector or shade holding means located below the said block and engaging therewith and means extending through the said block for supporting the 65 said reflector or shade holding means independently of the said block and the said cover.

4. An electric lighting fixture comprising an insulating block having an upper peripheral flange and having means for supporting an electric lamp therein and electrical connections therefor, a reflector or shade holding means below said block, ventilating passages extending through said block and 75 through the said reflector or shade holding means, a dome shaped cover for the said block, and passages extending through the aforesaid flange and connecting the space 80 between the said cover and the said block with the outer air.

5. In an electric light fixture, the combination of a block of insulating material having cavities therein for the reception of an incandescent lamp and its electrical connections, metallic parts extending through the said block for supporting the same and for supporting a shade or reflector below the same, and an insulating cover supported by the said block and extending beyond the 90 periphery thereof.

6. An electric lighting fixture comprising an insulating block having therein means for supporting an electric lamp and electrical connections therefor, a separable cover 95 extending over the top of the said block and supported thereby, a reflector or shade holding means, and means for supporting the latter independently of the said block.

7. An electric lighting fixture comprising 100 an insulating block having means therein for supporting an electric lamp and electrical connections therefor, a separable cover for the said block, a reflector or shade holding means located below the said block and 105 engaging therewith and means extending through the said block for supporting the said reflector or shade holding means independently of the said block and the said cover.

In witness whereof, I have hereunto set my hand this 22nd day of September 1913.

110 WILFRID LUMLEY.
